METHOD OF AND MEANS FOR REMOVING
GASEOUS IMPURITIES FROM ELECTRIC
DISCHARGE TUBES

Leo H. Dawson, Washington, D. C.

Application September 17, 1931, Serial No. 563,346

3 Claims. (Cl. 176—2)

(Granted under the act of March 3, 1883, as
amended April 30, 1928; 370 O. G. 757)

This invention relates to a method of, and means for, removing gaseous impurities from electric discharge tubes, and has for its object to provide a means and method whereby the necessity for long aging and treatment of such tubes to free them from water vapor and various gases will be obviated.

The single figure of the drawing shows the present invention applied to a luminous sign tube, 10 with certain parts in section.

In the manufacture of vacuum tubes, electric lamps, tubes for electric signs, etc., which are evacuated and then filled with one of the inert gases such as neon or argon, it is necessary to remove completely all of the active gases such as oxygen, nitrogen, etc., and water vapor from the tubes and carefully purify the inert gas with which the tube is to be filled. In previous manufacturing methods, the tubes were then baked 20 and aged for a considerable period under the action of an electric discharge. The method herein disclosed obviates much of the work involved as compared with other methods and very materially shortens the time required in the manufacture of such articles.

My invention is based upon the fact that misch metal, which is composed essentially of cerium, lanthanum, neodymium and praseodymium, has the property of uniting very readily with hydrogen, nitrogen, oxygen, other active gases and water vapor under the influence of an electric discharge, while the inert gases have no tendency to react with the misch metal.

The drawing shows a tube 1 for an electric sign, though it is to be understood that this is by way of illustration only and not of limitation. Electrodes 2 are sealed in the tube to provide for the electric discharge in the apparatus when in use. Tube 3 is connected to a vacuum pump 40 during the steps of manufacture concerned with this method and is provided with a stop cock to shut off the space within the tube 1 from the pump.

The auxiliary discharge device now to be described may be connected at any point to the article to be evacuated. It consists of a bulb 5 connected to the discharge tube 1 by a tube 6. Electrodes 7 are sealed into bulb 5, the said electrodes being made of aluminum to prevent cathodic disintegration. Sections 8 of misch metal are inserted into electrodes 7. These sections are preferably about one inch long, and the two sets of such sections are separated by about 55 four inches, though these dimensions are not

critical and may be varied within considerable limits.

The apparatus is connected as shown, and the tube 1 is filled with the desired inert gas at suitable pressure. A discharge between the electrodes 7 is set up and the tube 1 is evacuated to the desired degree, the discharge being continued until the active gases in the tube have combined with the misch metal to the extent that the atmosphere in tube 1 is of the requisite degree of purity. This method is especially effective in freeing the tubes of water vapor, which is usually the most difficult to remove.

The herein described invention may be manufactured and used by or for the Government of the United States of America for governmental purposes without the payment of any royalties thereon or therefor.

I claim:

1. An apparatus for removing active gases from an electric discharge tube, comprising an auxiliary tube adapted to be immediately connected to the space within said discharge tube between which an electric discharge may be set up, aluminum electrodes in said auxiliary tube, and pieces of misch metal inserted in said electrodes.

2. An apparatus for removing active gases from an electric discharge tube containing inert gas that is to remain in such tube during use thereof, comprising an auxiliary tube immediately connected to the space within the said discharge tube and disconnectable therefrom by sealing off the connecting portion, electrodes in said auxiliary tube between which an electric discharge may be set up, said electrodes being of metal substantially unaffected by cathodic disintegration and pieces of misch metal inserted in said electrodes.

3. An apparatus for removing active gases from an electric discharge tube containing inert gas that is to remain in such tube during use thereof, comprising an auxiliary tube immediately connected to the space within said discharge tube and disconnectable therefrom by sealing of the connecting portion, electrodes in said auxiliary tube between which an electric discharge may be set up, said electrodes being of metal substantially unaffected by cathodic disintegration and pieces of misch metal projecting from each electrode toward the other electrode.

LEO H. DAWSON. 105
